UNITED STATES PATENT OFFICE.

WILLIAM LEHMBERG, OF PHILADELPHIA, PENNSYLVANIA.

DESIGN FOR A BADGE OR INSIGNIA.

50,582.

Specification for Design.

Patented Apr. 10, 1917.

Application filed February 16, 1917. Serial No. 149,152. Term of patent 14 years.

To all whom it may concern:

Be it known that I, WILLIAM LEHMBERG, a citizen of the United States, residing in the city and county of Philadelphia and State of Pennsylvania, have invented a new, original, and ornamental Design for Badges or Insignias, of which the following is a specification, reference being had to the accompanying drawing, forming part thereof.

The figure is a face view of a badge or insignia, showing my new design.

I claim:—

The ornamental design for a badge or insignia, as shown.

WILLIAM LEHMBERG.
